PAPER BOARD CASK

Richard E. Blackburn, Amelia, Ohio, assignor to Container Corporation of America, Chicago, Ill., a corporation of Delaware

Application May 21, 1956, Serial No. 586,079

2 Claims. (Cl. 229—45)

This invention relates to a paper board cask for storing and shipping tobacco and other produce and has to do with the unit comprising the cask and the load of produce therein as well as with the cask itself.

My invention is directed to a paper board cask which may be produced at comparatively small cost and is of adequate mechanical strength to withstand the abuse to which it may be subjected in use. The cask of my invention comprises a tubular paper board body and end closure caps therefor secured upon the body by means comprising interengaging elements effective for restraining the closure caps against movement relative to the body in either direction lengthwise thereof while holding the caps seated tightly upon the ends of the body. More particularly, the securing means comprises oppositely directed interengaging rims on the caps and on the body so related that they are in endwise contact effective for restraining the caps against movement relative to the body lengthwise thereof, and a securing band drawn tightly about the rims so as to maintain them in compression radially of the body and prevent disengagement of the rims. A further and important feature of my invention is the provision of interior headers within the body of the cask above and below the load of produce therein, the headers being free from the body for movement relative thereto lengthwise thereof and serving to transmit the weight of the load of produce within the body to the closure caps in such manner as to reduce likelihood of rupture or tearing thereof. Further objects and advantages of my invention will appear from the detail description.

In the drawings:

Figure 1 is an elevational view, partly broken away, of a cask and a load of produce and headers therein embodying my invention;

Figure 2 is a top plan view of the loaded cask of Figure 1;

Figure 3 is a fragmentary sectional view, on an enlarged scale, of the loaded cask of Figure 1, taken substantially on line 3—3 of Figure 1;

Figure 4 is a plan view, on an enlarged scale, of a blank from which the body of the cask may be formed;

Figure 5 is a plan view of one of the closure caps embodying my invention;

Figure 6 is a plan view of one of the headers used in the loaded cask embodying my invention;

Figure 7 is a plan view of a modified form of header;

Figure 8 is an elevational view, partly broken away, of the upper portion of a modified form of cask embodying my invention;

Figure 9 is a fragmentary plan view, on a reduced scale, of one of the closure caps for the cask of Figure 8;

Figure 10 is a fragmentary sectional view, taken substantially on line 10—10 of Figure 8, on an enlarged scale; and

Figure 11 is a plan view of a second modified form of header.

The cask comprises a substantially cylindrical body 10

2

closed at each end by a cap 11. The body 10 is formed from two or more substantially rectangular blanks 12 of comparatively heavy or thick solid fibre board, each blank being cut and scored to provide a plurality of vertically disposed panels 13, a securing tab 14 extending from one end of blank 12 and flaps 15 extending from the ends of the panels 13. The blanks 12 are disposed end to end with the securing tab 14 of one blank underlying the end portion of the next adjacent blank and secured thereto by stitching or stapling, as shown in Figure 4, in which the second blank is indicated in dotted lines. The blanks 12 are bent into substantially circular form with the tab 14 at the free end of one of the blanks 12 disposed in underlying relation to the end portion of the other blank and secured thereto by stitching or stapling. That produces the substantially cylindrical body 10 of the cask. The flaps 15 are then bent or folded outwardly into parallelism with the body 10 so as to provide therewith, at each end of the body, a substantially continuous rim with flaps 15 disposed in substantially concentric spaced relation to the adjacent end portion of the body and defining therewith a channel opening inwardly lengthwise of the body. Each of the caps 11 comprises a disc cut from comparatively thick or heavy solid fibre board and flaps 16 extending radially outward from the periphery of the disc and integrally attached thereto along fold lines 17. Each of the flaps 16 is provided with a transverse fold line 18 spaced somewhat nearer its outer end than its inner end for a purpose to be described presently.

After the body 10 of the cask has been formed in the manner above described, with the flaps 15 thereof bent or folded over so as to extend along the end portions of body 10 as in Figures 1, 2 and 3, a cap is placed upon the end of body 10, the flaps 15 of body 10 are swung outward and the flaps 16 of cap 11 are folded about flaps 15, and the interfolded flaps 15 and 16 are then folded inwardly against the body 10, as will be clear from Figure 3 in which the steps of folding the flaps 15 outward and folding the flaps 16 about flaps 15 is indicated in dotted lines. The flaps 16 of cap 11 are folded along the fold lines 18 about flaps 15 of body 10, as will be understood from what has been said, each of the folded cap flaps 16 then comprising an outer arm 19 and an inner arm 20 extending about flap 15 of body 10. Referring further to Figure 3, it will be noted that the upper edge of arm 20 contacts flap 15 at the juncture thereof with body 10 and the lower edge of flap 15 contacts the cap flap 16 at the juncture of the arms 19 and 20 of flap 16. The flaps 15 of body 10 provide a substantially continuous channel member, in conjunction with the adjacent end portion of body 10, which opens inwardly lengthwise of body 10, and the folded flaps 16 of the cap 11 provide a substantially continuous channel member or rim which opens outwardly of body 10 lengthwise thereof, i. e. toward the ends of the body. The two channel rims thus provided are interengaged as above described and each thereof has contact with the other rim effective for restraining the cap against movement in either direction lengthwise of body 10 relative thereto. After the rims of the cap and the body have been interfolded and interengaged in the manner above described, a securing band 21, conveniently of metal strapping, is pulled tightly about the outer arms 19 of flaps 16, the ends of the band 21 being secured together by a connector 22 of known type and in a known manner. The band 21 compresses the elements of the interengaging rims radially of body 10 and effectively guards against possible disengagement thereof.

After a cap has been secured upon one end of body 10 of the cask in the manner above described, the cask is turned with its closed end down, for reception of the material or produce to be placed therein. Before load-

ing the cask a lower header is placed therein upon the upper face of the then bottom cap closing the bottom of body 10. Assuming tobacco or analogous produce is to be placed in the cask, a header such as that shown in Figure 6 preferably is used. It comprises a rim 23 of substantial width and an inner body portion secured in the rim formed, in the header shown, of two strips 24 of wood of substantial thickness disposed in crossing relation one perpendicular to the other and secured to the rim 23. The header 25 thus produced is of open work construction and the rim 23 projects a substantial distance beyond the strips 24 lengthwise of body 10 and toward the adjacent closure cap 11. After the header has been placed within the body upon the lower cap 11, the produce, such as leaf tobacco, is loaded into the body 10 of the cask onto the header, the cross pieces of which are of adequate strength to support the load of tobacco. The body 10 is substantially filled with the tobacco and then an upper header 25 is placed upon the load of tobacco, after which the top closure 11 is secured to the upper end of body 10 in the manner previously described, thus completing the loaded cask. The headers 25 are free from body 10 for relative movement lengthwise thereof and fit the interior thereof snugly but not tightly. If the loaded cask is lifted lengthwise without a support beneath it, the weight of the load is transmitted by the lower header through rim 23 to the bottom closure cap adjacent the interengaging rims of the cap and the cask body, to which the load is transmitted under compression lengthwise of the cask body so that the interengaging rim structure is capable of supporting the load without risk of rupture or tearing of the parts thereof. That avoids transmission of the load to the central areas of the cap, which might fracture or tear under the weight of the load of produce within the cask. It has been assumed, for purposes of description, that the produce within the cask is tobacco or other produce requiring ventilation, for which the open work headers 25 preferably have been described as used, it being noted that each of the closure caps 11 is provided with ventilation openings 27. If the produce placed in the cask does not require ventilation, a solid header, such as the header 28 shown in Figure 7 may be used. The header 28 may be in the form of a disc of wood of substantial thickness capable of supporting the weight of the load, or of any other suitable material which will support the load, and is of a diameter to fit the interior of the body 10 of the cask. As will be understood, two headers preferably are used, one at the bottom of the load and the other at the top of the load, the header at the bottom of the cask body 10 serving to distribute the weight of the load throughout the full extent of the upper face of the lower closure cap 11 so that the weight of the load is transmitted to the rim portion of the cask body and the closure cap thereby guarding against rupture or tearing of the cap in substantially the same manner as above described.

The modified form of cask of Figures 8 to 10 comprises body 10^a formed from two or more blanks 12^a cut and scored to provide vertically disposed panels 13^a, a securing tab 14^a extending from one end of blank 12^a and flaps 15^a, one of which is shown in Figure 10, extending from the ends of panels 13^a. The blanks 12^a are disposed end to end with the securing tab 14^a of one blank overlying the end portion of the next adjacent blank and secured thereto by stitching or stapling and preferably also by adhesive, indicated by stippling 14^b, as shown in Figure 8. The flaps 15^a are folded outwardly into parallelism with the body 10^a so as to provide therewith, at each end thereof, a substantially continuous rim disposed in substantially concentric spaced relation to the adjacent end portion of the body 10^a and defining therewith a channel opening inwardly lengthwise of the body, as before.

Each end of the body 10^a is closed by a cap 11^a com-

prising a disc, preferably cut from the same material as the body, and flaps 16^a and 16^b extending radially outward from the periphery of the disc and integrally attached thereto along fold lines 17^a, the flaps 16^a and 16^b being preferably, though not necessarily, arranged in alternating relation. Each of the flaps 16^a and 16^b is provided with a transverse fold line 18^a spaced somewhat nearer its outer end than its inner end. Each of the flaps 16^b is further provided, at its midportion, with two parallel lengthwise slits 16^c extending across and approximately an equal distance above and below the fold line 18^a. The slits 16^c define between them a web element 16^d integrally attached at its ends to flaps 16^b along fold lines 16^e. Preliminary to applying the closure cap 11^a to the end of body 10^a a securing member, conveniently a steel wire 20^a, is threaded through the slits 16^c so as to extend across the outer faces of elements 16^d, the inner faces of flaps 16^b and the outer faces of flaps 16^a. The cap 11^a, with the wire 20^a threaded therethrough as above, is then mounted on the end of the body 10^a in the manner previously described, with the flaps 16^a and 16^b interfolded with the flaps 15^a and the elements 16^d folded outwardly toward the adjacent end of body 10^a and disposed adjacent the inner ends of flaps 15^a, as shown in Figure 10. The cap 11^a is then pressed firmly onto the end of body 10^a and the wire 20^a is pulled tight about body 10^a under substantial tension, by suitable known means, and its ends are twisted together, at 20^b, or secured together in any suitable known manner. The cap 11^a is thus tightly secured upon body 10^a so as to guard effectively against dislodgement of the cap.

After a cap 11^a has been secured upon one end of body 10^a, the latter is then placed upon a suitable support with the closed end down, for loading. Preliminary to loading a lower header is placed within the cask upon the upper face of the then bottom cap. The header may be either of the forms shown in Figures 6 and 7, or may be of the form shown in Figure 11 comprising a rim 23^a and three crossed strips of wood 24^a secured to each other and to rim 23^a providing therewith the header 25^a. When the cask has been filled, an upper head is placed upon the top of the load and a closure cap 11^a is then secured upon the upper end of the cask in the manner above described. The cap 11^a is shown as not provided with ventilation openings, which may not be necessary in certain cases, but may be provided with such openings if necessary or desired, as will be understood.

As will be seen from a comparison of Figures 3 and 10, in each form of the cask of my invention shown by way of example, the closure caps have flaps respectively comprising an outer arm extending inwardly of the cask body in proximity to the corresponding body flap and an inner arm extending outwardly of the body and fitting between the corresponding body flap and the adjacent portion of the body, the flaps of the cap being secured about the body by a band secured under tension about the body and exerting pressure radially thereof.

It will be understood that changes in detail may be resorted to without departing from the field and scope of my invention, and I intend to include all such variations, as fall within the scope of the appended claims, in this application in which the preferred form only of my invention has been disclosed.

65 I claim:

1. In a cask of tobacco and analogous produce, a tubular paper board body having at each end an integral exterior rim extending inwardly of said body lengthwise thereof and disposed in substantially concentric spaced relation thereto, a closure cap at each end of said body seating thereon and having an integral rim of channel cross section comprising a radially outer arm at the outer face of the corresponding body rim and a radially inner arm integrally attached at its axially inner 70 end to the corresponding end of said outer arm, said

inner arm fitting snugly between said body and body rim with its axially outer edge contacting said body rim at the juncture thereof with said body effective for restraining said cap against movement away from said body, a securing band at each end of said body secured under tension about said body and cap rims effective for maintaining them under compression radially of said body, and top and bottom headers within said cask body between said body of produce and said caps, said headers respectively comprising a unitary rim and a body portion secured therein, said header rim having an exterior diameter approximately the same as the interior diameter of said cask body and being free from the latter, the rim of each header extending axially thereof beyond the body portion thereof toward the adjacent cap for seating on the inner face of the latter in proximity to the rim thereof and the body portion of the header being effective for supporting the body of produce out of contact with the corresponding closure cap.

2. In a paper board cask, a tubular body closed at its bottom and provided at its top with integrally attached downwardly extending exterior flaps spaced from said body, a top closure cap seating on the top of said body and having integral flaps respectively comprising a downwardly extending arm and an upwardly extending arm attached at its lower end to the lower end of said downwardly extending arm, said downwardly extending arms of said cap flaps directly seating for their full length on the outer faces of said body flaps in face to face contact therewith and being restrained thereby against transverse

10
15
20
30

buckling inwardly toward said body and said upwardly extending arms of said cap flaps fitting for their full length snugly between said body flaps and the corresponding portions of said body in face to face contact therewith and being restrained thereby against transverse buckling both inwardly toward and outwardly away from said body, said upwardly extending arms of said cap flaps contacting at their upper ends said body flaps at the junctures thereof with said body and said body flaps contacting at their lower ends said cap flaps at the junctures of said arms of the latter flaps whereby said upwardly extending arms of said cap flaps and said body flaps provide compression members resisting movement of said closure cap away from said body and said downwardly extending arms of said cap flaps provide tension members resisting movement of said closure cap away from said body, and a securing band drawn tightly about said outer arms of said cap flaps effective for maintaining all of said flaps under pressure contact radially of said body.
